Walter M. Wear,
William L. Drake

By *Franklin Pendleton* Attorney

UNITED STATES PATENT OFFICE.

WALTER M. WEAR AND WILLIAM L. DRAKE, OF DEWAR, OKLAHOMA.

NUT LOCK.

1,427,566.

Specification of Letters Patent. Patented Aug. 29, 1922.

Application filed August 30, 1921. Serial No. 496,825.

To all whom it may concern:

Be it known that we, WALTER M. WEAR and WILLIAM L. DRAKE, citizens of the United States, residing at Dewar, in the 5 county of Okmulgee, State of Oklahoma, have invented certain new and useful Improvements in Nut Locks; and we do hereby declare the following to be a full, clear, and exact description of the invention, such 10 as will enable others skilled in the art to which it appertains to make and use the same.

This invention relates to new and useful 15 improvements in locking devices for rail joints and particularly to locks for the nuts of the rail joint bolts.

One object of the invention is to provide 20 a device of this character which is adapted to be applied to the bolts before the nuts are applied, and which cooperates with the nuts and with the tread and base of the rail ends to prevent turning of the nuts.

Another object of the invention is to provide 25 a device of this character which is simple in construction, easily applicable to the bolts of any railway joint, and one which can be manufactured at a comparatively low cost.

Other objects and advantages will be apparent 30 from the following description when taken in connection with the accompanying drawing.

In the drawing:

Figure 1 is a side elevation of a rail joint 35 showing the invention in applied position.

Figure 2 is a longitudinal central sectional view through the locking plates, on the line 2-2 of Figure 1.

Figure 3 is a perspective view of the locking 40 device removed from the rail and bolts.

Referring particularly to the accompanying drawing 10 represents a pair of rail ends having the bolts 11 disposed therethrough and on which are engaged the nuts 12. Dis-

45 posed longitudinally of the webs of the rail ends, and between the tread and base portions thereof, is a metal plate 13 having a number of openings 14 for receiving the threaded ends of the bolts therethrough. One 50 end of the plate 13 is formed with the rolled portions 15, and disposed between these portions is a similar portion 16 of the adjacent end of a metal plate 17, of the same dimen-

sions as the plate 13, and being disposed to lie against the outer face of said plate 13. 55 A pin 18 is disposed through the portions 15 and 16 whereby the plate 17 is hinged to the plate 13. At the other end of the plate 13 there is formed a longitudinally extending tongue 19 which, when the plates are 60 properly positioned with respect to the rail ends and the bolts, is bent forwardly and across the outer face of the adjacent end of the plate 17, to retain said plate against outward movement. At regularly spaced intervals along the plate 17, there are made pairs of diagonal intersecting incisions which result in the formation of the triangular tongues 20, which, when bent outwardly, permit the threaded ends of the bolts, with 70 their nuts, to extend therethrough. After the bolt ends and nuts are properly positioned between the tongues 20, the outer ends of the said tongues are bent inwardly and transversely on the outer faces of the nuts 75 and against the side faces thereof, with the result that the nuts will be held against rotation on the bolts, in either direction.

It will be noted that the plates 13 and 17 are of the same width, and that this 80 width is equal to the distance between the lower face of the treads of the rail ends and the upper faces of the base flanges thereof, with the result that the plates are confined between such points against movement 85 vertically. The nuts retain the plate 13 against outward or longitudinal movement, and thus retain the plate 17 against movement with respect thereto. The hinged connections at one end of the plates 13 and 17, 90 together with the tongue 19 at the other end, serve to firmly bind the two plates together. Thus is formed an effective lock for the nuts of the railway joint bolts, the plates 13 and 17 performing the duty of a 95 fishplate.

What is claimed is:

A nut lock for a rail joint comprising a pair of elongated plates hinged together at one end, the other end of one of the plates 100 having a tongue arranged to be bent around into embracing engagement with the adjacent end of the other plate, the first plate having bolt receiving openings, and tongues on its upper and lower edge portions at 105 points between the openings and embracing

the upper and lower edge portions of the other plate, the other plate having nut receiving openings and triangular tongues at the sides of the said openings engaging with the side faces of the nuts, said tongues having their outer ends bent into engagement with the outer faces of the nuts.

In testimony whereof, we affix our signatures, in the presence of two witnesses.

WALTER M. WEAR.
WILLIAM L. DRAKE.
